UNITED STATES PATENT OFFICE.

FREDERICK G. GRUEN, OF CINCINNATI, OHIO.

DESIGN FOR A WATCH-DIAL.

40,280.

Specification for Design.

Patented Oct. 5, 1909.

Application filed April 1, 1909. Serial No. 487,364. Term of patent 14 years.

To all whom it may concern:

Be it known that I, FREDERICK G. GRUEN, a citizen of the United States, residing at Cincinnati, in the county of Hamilton and State of Ohio, have invented a new, original, and ornamental Design for Watch-Dials, of which the following is a specification, reference being had to the accompanying drawing, forming part thereof.

The figure is a plan view of a watch dial showing my new design.

The appearance of the dial is metallic. The dial has a central field containing an engraved spray of leaves and flowers. Beyond the central field are two concentric fields of fine circular lines, the outer field being of darker or duller appearance. In the inner circular field are numerals for the hour divisions and the outer circular field contains

large and small bright or glistening dots, the large dots being at the five-minute division points and the smaller dots being at the minute division points between the five-minute division points. In the lower portion of the dial and intersecting both the central field and the inner circular field is the second hand field exhibiting fine concentric lines and around the margin of this field appear usual numerals and markings denoting divisions of a minute.

I claim:

The ornamental design for a metallic watch dial as shown and described.

FREDERICK G. GRUEN.
